US00D922352S

(12) **United States Design Patent** (10) **Patent No.:** **US D922,352 S**
Byrd et al. (45) **Date of Patent:** **** Jun. 15, 2021**

(54) **SPEAKER**

(71) Applicant: **Dolby Laboratories Licensing Corporation**, San Francisco, CA (US)

(72) Inventors: **Grayson H. Byrd**, San Francisco, CA (US); **Cody Michael Proksa**, San Francisco, CA (US); **Lucas E. Saule**, San Francisco, CA (US); **Peter Michaelian**, San Francisco, CA (US); **Brian Edward Renz**, Millbrae, CA (US); **John Carson Stewart**, San Francisco, CA (US); **Vincent Voron**, Menlo Park, CA (US)

(73) Assignee: **DOLBY LABORATORIES LICENSING CORPORATION**, San Francisco, CA (US)

(**) Term: **15 Years**

(21) Appl. No.: **29/675,792**

(22) Filed: **Jan. 4, 2019**

(51) **LOC (13) Cl.** **14-01**

(52) **U.S. Cl.**

USPC **D14/214**; D14/204
(58) **Field of Classification Search**

(57) **CLAIM**

The ornamental design for a speaker, as shown and described.

DESCRIPTION

FIG. 1 is a front perspective view of a speaker showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The dashed broken lines in the figures illustrate portions of the speaker that form no part of the claimed design.

1 Claim, 4 Drawing Sheets
